Patented Feb. 14, 1922.

FIG. 1.

FIG. 2.

FIG. 3.

Inventor

JOHN L. WILCOX

By

Attorney

Richard J. Cook

UNITED STATES PATENT OFFICE.

JOHN L. WILCOX, OF SEATTLE, WASHINGTON.

IRONING BOARD.

1,406,515.

Specification of Letters Patent. Patented Feb. 14, 1922.

Application filed January 26, 1921. Serial No. 439,951.

To all whom it may concern:

Be it known that I, JOHN L. WILCOX, a citizen of the United States, and a resident of the city of Seattle, county of King, State 5 of Washington, have invented certain new and useful Improvements in Ironing Boards, of which the following is a specification.

My invention relates to improvements in ironing boards, and has for its principal 10 object to provide an ironing board equipped with means whereby it may be clamped upon and held functionally in spaced relation from the top of a table or the like so that clothes may be ironed thereon.

15 It is also an object of the invention to provide a holding or clamping device of the above character that is detachable from the board and which is provided with a protected stand portion whereupon hot irons 20 may be placed when the board is in use.

Other objects of the invention reside in the construction of the board in such manner that it will receive the holding device, and in the manner of constructing and applying the latter to the board.

25 In accomplishing these and other objects of the invention, I have provided the improved details of construction, the preferred forms of which are illustrated in the accompanying drawings, wherein—

Figure 1 is a side view of an ironing board and its holding device constructed in accordance with the present invention, showing the device in functional position for 30 holding the board upon a table.

Figure 2 is a longitudinal section of the same.

Figure 3 is a detail perspective view of the board and holding device removed therefrom.

40 Referring more in detail to the drawings—

1 designates an ironing board which may be of the usual shape and construction and 45 provided centrally at a point adjacent the end of its larger portion with a longitudinally directed slot 2 as shown in Figure 3, and on its under side at this end, with two transverse bars 3 and 4, the bar 3 being 50 adjacent the end of the board to strengthen the latter and the bar 4 being spaced at some distance from the opposite end of the slot, and is fixed hingedly to the board so that at such times when not serving as a support 55 it may be folded, toward the slot, against the board to be out of the way.

The holding device embodying the principal part of the present invention comprises a head portion 6 provided at one side with a laterally extending arm 7 and on 60 its under side with a hook portion 8 forming a notch 9 opening in the direction of the extension of the arm. When the device is applied to the board for use, the arm is extended downwardly through the slot 2 and 65 then turned in such manner as to underlie and support the board thereon from the top 10 of a table, as shown in Figures 1 and 2, with the hook portion 8 projecting beneath the edge of the table so that pressure on 70 the free end of the board will not cause it to tilt.

Located in the face of the bar 4 adjacent the slot 2 and alining with the latter is a notch 12 adapted to receive the end of the 75 arm 7 therein so that the holding device is held substantially rigid.

The head portion 6 is of such width that it will fill the slot 2 and is provided at the end opposite the edge from which the arm 80 7 extends with a shoulder 15 adapted to engage the top of the board to limit the inward movement of the head and to hold the board rigidly thereon. The edge of the head, from adjacent the shoulder downward, 85 is curved radially about the vertical edge opposite the shoulder so that it may be placed easily in or removed from position.

Fixed upon the head is a horizontal plate 16, which may be covered with an asbestos 90 sheet 17, or the like, so that when one is working he may place the iron upon the stand thus provided.

Such a device, it is apparent, can be used to effectively support an ironing board upon 95 a table or stand, and will hold the latter spaced at such distance from the top of the table that clothes can be drawn under the board.

It will be noted also that the device will 100 hold the board perfectly rigid during use and will also provide a convenient stand upon which the hot irons may be placed without danger.

When not in use the device can be readily 105 removed so that, with the board it may be stored in a small space.

Having thus described my invention, what I claim as new therein and desire to secure by Letters Patent, is:

110 1. The combination with an ironing board having a longitudinally directed slot in one

- end thereof and a transverse supporting bar fixed thereto, of a holding device extendable downwardly within said slot into locked relation with the board and having a horizontal notch therein for receiving the edge of a table or the like whereon the board is mounted in such manner as to cooperate with said cross bar in holding the board in position.
- 10 2. The combination with an ironing board having a longitudinally directed slot in one end thereof and a transverse supporting bar fixed thereto, of a holding device comprising a head portion extendable downwardly with-
15 in said slot into locked relation with the board and having a horizontally directed arm extending beneath the board into locked relation with the cross bar; said head having a horizontal notch beneath said arm to receive the edge of a table or the like whereon the arm is supported and cooperating with said cross bar in holding the board rigid.
- 20 3. The combination with an ironing board having a longitudinally directed slot in one

end thereof and a cross bar fixed thereto 25 between said slot and opposite end of said board having a notch therein in alinement with said slot, of a removable holding device comprising a head portion adapted to be extended downwardly within said slot, 30 provided at one edge with a shoulder for engaging the board to limit the inward movement of the head, and at its opposite edge having a laterally directed arm for underlying the board and adapted at its 35 outer end to be extended into said bar notch; said head being curved radially from the shoulder downwardly and in the direction of the arm and forming a hook portion extending in the direction of the arm and providing 40 a notch between the two for receiving the edge of a table or the like whereon the board is mounted to retain the board substantially rigid.

Signed at Seattle, Washington this 21st 45 day of January, 1921.

JOHN L. WILCOX.
